UNITED STATES PATENT OFFICE.

ARDEN S. FITCH, OF NEW YORK, N. Y.

MAGNETO-ELECTRIC MACHINE.

SPECIFICATION forming part of Letters Patent No. 410,966, dated September 10, 1889.

Application filed August 21, 1889. Serial No. 321,482. (No model.)

To all whom it may concern:

Be it known that I, ARDEN S. FITCH, of the city, county, and State of New York, a citizen of the United States, have invented certain new and useful Improvements in Magneto-Electric Machines, of which the following is a full, clear, and exact description, reference being had to the accompanying drawings, forming part of this specification.

10 My invention relates to magneto-electric machines of the class used in generating an electric current for firing fuses in blasting operations, and more particularly to the magneto-electric machine of this class for which 15 I filed application for Letters Patent on June 20, 1889, Serial No. 314,949.

The object of my invention is to provide an effective and convenient means of actuating the device within the inclosing-case of the 20 machine which operates to rotate the rotary armature to generate the current.

My invention consists in the combination, with the armature-operating device adapted to swing or rotate in its movement to operate 25 the armature, of a bar adapted to be seated in or upon the armature-operating device and to slide or move longitudinally transversely thereof or therein, whereby when the machine is inclosed in its case or box the bar, by its 30 movement transversely of and in or upon the armature-operating device, may be caused to pass within and be practically inclosed in the box, so that when the machine is not in use it is thus in convenient portable condition, 35 and whereby when it is desired to use the machine to generate an electric current the bar may be readily moved or drawn longitudinally in or upon the armature-operating device transversely thereof and through and 40 caused to extend or project exteriorly of a wall of the box, so that it may be grasped by the operator and vibrated to effect the desired movement of the armature-operating device to rotate the armature, all as hereinafter particularly described, and as more at length 45 recited in the claims.

Figure 1 is a plan of a magneto-electric machine containing my invention. Fig. 2 is a vertical central section of the armature-operating device and its connected mechanism and showing my invention, and Fig. 3 is an end elevation of the machine.

M represents the magnet; N, the rotary armature having a pinion n on its arbor.

A is the armature-operating device, which 55 in this machine is, as shown, in the form of a toothed segment journaled on a stud or shaft-pin a . This segment is shown as engaging a pinion a' , which in turn, by means of a clutch composed of a ratchet a^2 and pawl a^3 , communicates motion in one direction only to a gear a^4 , which engages the armature-pinion n . The segment A, by a swing or vibration on its shaft or pivot in one direction, thus operates to effect the rotation of the armature 65 N, while during the reverse vibration of the segment the armature remains at rest.

B is a bar, preferably of metal and of a length to adapt it to the uses hereinafter set forth. This bar is arranged to be seated in 70 or upon the segment A and to move or slide longitudinally transversely of said segment. To accomplish this arrangement, the segment A is preferably provided with an extension or hub a^5 , and this hub has the transverse slot a^6 formed in it, in which slot the bar B is fitted to slide longitudinally, as shown. The bar may be furnished with a ring-like handle b at its upper end, and is desirably provided with a pin or projection b' at its 80 lower end to limit its movement in one direction in the slot a^6 .

C is the inclosing-case of the machine. In arranging the machine in its said case it is desirable to provide a partition c near one of 85 the end walls c' of the case, and to permit the hub a^5 to extend through an aperture in this partition, and to project into a corresponding recess c^2 in the box-wall, as shown. By this means a bearing for the hub is furnished in the partition, and the bar B may be given play in the hub b^5 within the space or chamber between the partition c and wall c' . The bar B is desirably of such a length that when it is slid downward in the slot a^6 and its 90 lower end rests upon the box-bottom its upper end will project but slightly above the box-lid through a slot c^3 formed therein and extending transversely thereof, as shown.

Now, it is evident that by means of the bar 100 B, seated and adapted to move or play longitudinally transversely of the armature-operating segment A, as described, when the machine is not in use, the bar may be slid down-

ward into and be practically inclosed in the case or box C, and that when it is desired to employ the machine to generate an electric current by the rotation of the armature the bar B may be readily slid upward in the segment, and thus caused to project through the slot c^3 in the box-lid, where it will be in position adapting it to be conveniently grasped by the hand of the operator and to serve as 10 a lever to vibrate the segment to effect the rotation of the armature, as illustrated in Fig. 3, by being swung from its limit of movement in one direction in the slot c^3 to its limit of movement in the opposite direction 15 therein.

When the use of the machine is discontinued, the bar may be again slid within the box.

By means of the partition c and the projection through the same of the hub a^5 , so 20 that the bar B may play in a chamber which is distinct from that in the case which contains the magnet and its connected devices, the exclusion of dust and similar matter 25 from the main chamber of the case, which may pass through the slot c^3 in the lid, is effected.

Any known and equivalent means for giving the bar B the described seat in or upon 30 the armature-operating device A and the described longitudinal play therein may be employed in place of the slotted hub a^5 without departure from the essential feature of my invention.

35 What I claim as my invention, and desire to secure by Letters Patent, is—

1. In a magneto-electric machine, the combination, with the armature-operating device adapted to swing or rotate in its movement

to operate the armature for the generation of 40 an electric current, of a bar seated in or upon said armature-operating device and adapted to slide or move longitudinally therein and transversely thereof, substantially as and for the purpose set forth.

2. In a magneto-electric machine, the combination, with a journaled toothed segment for operating the rotary armature to generate an electric current, of a bar seated in or upon 50 said segment and adapted to slide or move longitudinally therein and transversely thereof, substantially as and for the purpose set forth.

3. In a magneto-electric machine, the combination, with a journaled toothed segment for operating the rotary armature to generate 55 an electric current and provided with a lateral extension or hub in which is a transverse slot, of a bar seated in and adapted to play longitudinally in said slot in said hub, substantially as and for the purpose set forth. 6c

4. In a magneto-electric machine, the combination, with a journaled toothed segment for operating the rotary armature to generate an electric current and provided with a laterally-extended hub having a transverse slot, 65 of an inclosing-case having therein an apertured partition through which said hub extends and in which it has bearing, together with a bar seated and having play longitudinally in said slotted hub outside said partition, and a lid or wall on said case provided with a slotted aperture to permit the bar to project exteriorly of the inclosing-case, substantially as and for the purpose set forth. 70

ARDEN S. FITCH.
